UNITED STATES PATENT OFFICE.

ARTHUR E. SNOW, OF NORWOOD, OHIO, ASSIGNOR TO THE AMERICAN LAUNDRY MACHINERY COMPANY, OF NORWOOD, OHIO, A CORPORATION OF OHIO.

PUFF-IRON.

1,376,046.

Specification of Letters Patent. Patented Apr. 26, 1921.

Application filed July 12, 1919. Serial No. 310,447.

To all whom it may concern:

Be it known that I, ARTHUR E. Snow, a citizen of the United States, residing at Norwood, in the county of Hamilton and 5 State of Ohio, have invented certain new and useful Improvements in Puff-Irons, of which the following is a specification.

This invention relates to apparatus for pressing garments, and more particularly to 10 what are known as puff irons.

Garment pressing machines embodying relatively movable pressing members between which the garments or fabrics are pressed are usually provided with a suitably 15 located puff iron comprising a hollow smooth surfaced member of spherical, oval, or other form to which steam is supplied for heating the iron and from which it issues through small perforations for moistening a garment or fabric passed over the 20 iron.

The object of the present invention is to improve the construction of the puff iron in a manner to prevent the collection of 25 water of condensation therein, to maintain a supply of live steam for heating the iron, and to enable the flow of steam to and through the steaming perforations to be turned on and off as desired.

30 Further objects of the invention are in part obvious and in part will appear more in detail hereinafter.

In the drawings, Figure 1 represents a 35 side elevation of one form of garment pressing machine embodying the invention, the upper head of the machine being shown in section; Fig. 2 is a detail sectional view, on a larger scale on the line 2—2, Fig. 1; and Fig. 3 is a detail section on the line 3—3, 40 Fig. 2.

The garment pressing apparatus illustrated in the drawings comprises a suitable frame 1 provided with the usual work table 2 and post 3 supporting the stationary hollow pressing bed or buck 4 on which the fabric or garment to be pressed is laid. The frame includes an upright portion on which is pivoted at 5 a swinging arm or lever 6 provided at one end with a counterweight 7 45 and at its opposite end with a hollow upper pressing member or head 8, to the inner chamber 9 of which live steam is supplied through the pipe 10.

The puff iron is indicated generally at 11, 55 Fig. 1. It is supported by a pipe 12 thread-

ed into an opening into the head 8 so that said pipe forms a conduit for conducting live steam from the chamber of the head to the interior of the puff iron, as will appear.

The puff iron comprises a lower member or base 13 of hollow form provided with a horizontal upper cross wall 14 forming an inner chamber 15 in communication with the chamber 9 of the head 8 through the 65 pipe 12. Around the periphery of the wall 14 the outer wall of the body 13 is continued upwardly to form a circumferentially extending rim or flange 16, so that the upper portion of the base 13 is in the form of a 70 shallow pan. The upper member or cover of the puff iron is also in the form of a hollow shell, its outer wall 17 being curved and at its edge meeting the edge of the flange 16, the outer surface of both members being 75 polished off smooth so that the puff iron as a whole has a curved smooth surface. At its center the upper member 17 is provided with a depending post 18 threaded to receive a clamping screw 19 which is passed through 80 an opening in the sleeve 20 of the lower member. By tightening up this screw the two parts of the iron are firmly secured together.

When the upper and lower parts of the 85 iron are secured together the wall 14 divides the interior space into two chambers to wit, the steam supply chamber 15 before referred to in the lower member or base, and a chamber 21 surrounding the post 18 in the 90 upper member or cover. Flow of steam from chamber 15 to chamber 21 is controlled by suitable valve mechanism. The valve mechanism shown includes a T 22 threaded into the wall 14 and having one of its branches 95 provided with a tapering valve seat 23 at the inner end of the port 24. The valve includes a rod 25 threaded into the opposite branch of the T and having a conical end valve portion coöoperating with the seat 23. 100 This rod is extended outwardly to the wall of the puff iron where its outer end is provided with suitable means for turning the same, such as the screw driver slot 26 accessible through an opening in the wall. 105

If the valve is screwed down to its seat flow of steam from chamber 15 to chamber 21 is cut off. Nevertheless, as soon as the supply of steam is turned on to the machine the steam flows from chamber 9 and thence 110

into chamber 15. This live steam keeps the puff iron hot so that it is available for use as soon as the pressing members are hot. To moisten garments applied to the puff iron 5 the valve 25 is moved away from its seat, so that steam flows to chamber 21, from which it issues through a series of closely spaced small openings or perforations 27 in the puff iron wall. Any water of condensation 10 formed in chamber 15 drains back to the hollow head through the pipe 12. Any water of condensation formed in chamber 21 does not escape to the outside of the puff iron either through the openings 27 or 15 through the crack or joint between the upper and lower members of the iron, but collects in the shallow cavity within the flange 16 and above the wall 14, and this heated wall thereupon vaporizes the collected 20 moisture so that it is carried off through the openings 27 with the steam supply.

What I claim is:—

1. A puff iron, comprising a hollow chambered cast metal base having a horizontal 25 upper wall and an integral upwardly extending peripheral flange surrounding the same and forming a shallow pan shaped receiver for water of condensation, an inverted dome shaped perforated thin metal cover 30 secured thereto with its edge resting upon said peripheral flange, and forming with

said receiver a steam distributing chamber above said wall, means for supplying steam to the chamber in said base for heating the iron and vaporizing water of condensation 35 collected upon said wall, and means for controlling the flow of steam from the base chamber to the chamber above said wall to be distributed through said perforated cover.

2. A puff iron, comprising a hollow chambered cast metal base having a horizontal upper wall and an integral upwardly extending peripheral flange surrounding the same and forming a shallow pan shaped receiver for water of condensation, an inverted 40 dome shaped perforated thin metal cover secured thereto with its edge resting upon said peripheral flange, and forming with said receiver a steam distributing chamber above said wall, means for supplying steam to the 45 chamber in said base for heating the iron and vaporizing water of condensation collected upon said wall, and valve means extending horizontally through the side wall of said iron and accessible from the outside 50 thereof and capable of being set in various positions for controlling the flow of steam from the base chamber to the chamber above said wall to be distributed through said perforated cover.

In testimony whereof I affix my signature.
ARTHUR E. SNOW.
